CLAIM

The ornamental design for an exerciser for the muscles of the pelvis, as shown and described.

DESCRIPTION

FIG. 1 is a perspective view of the exerciser for the muscles of the pelvis of this invention;

FIG. 2 is a top plan view thereof and a bottom plan view thereof which is identified thereto;

FIG. 3 is a left side elevational view thereof, the right side elevational view being a mirror image thereof;

FIG. 4 is a front elevational view thereof; and,

FIG. 5 is a rear elevational view thereof.
